(57) **CLAIM**

The ornamental design for keyboard/keyboard enclosure, as shown and described.

DESCRIPTION

FIG. 1 is a rear perspective view of a keyboard/keyboard enclosure of the instant invention.

FIG. 2 is a front perspective view of the keyboard/keyboard enclosure of FIG. 1.

FIG. 3 is a rear view of the keyboard/keyboard enclosure of FIG. 1.

FIG. 4 is a front view of the keyboard/keyboard enclosure of FIG. 1.

FIG. 5 is a top view of the keyboard/keyboard enclosure of FIG. 1, the bottom view being a mirror image thereof.

FIG. 6 is an end view of the keyboard/keyboard enclosure of FIG. 1.

FIG. 7 is another end view of the end of the keyboard/keyboard enclosure opposing that shown in FIG. 6; and,

FIG. 8 is a front view of the keyboard/keyboard enclosure of FIG. 1 with a keypad overlay positioned on the front surface of the keyboard/keyboard enclosure.

The broken lines shown in the drawings illustrate portions of the keyboard/keyboard enclosure and keypad overlay, and form no part of the claimed design. Further, the cord, also in broken lines in FIG. 1, is shown broken away to indicate an indeterminate length.
